No. 14,974

Apr. 22, 1884

UNITED STATES PATENT OFFICE.

SAMUEL W. WILSON, OF NEW YORK, N. Y.

DESIGN FOR PAPER.

SPECIFICATION forming part of Design No. 14,974, dated April 22, 1884.

Application filed March 1, 1884. Term of patent 14 years.

To all whom it may concern:

Be it known that I, SAMUEL W. WILSON, of New York, in the county of New York and State of New York, have invented a certain 5 new and original Design for Paper, of which the following is a specification.

My design is applicable to various kinds of paper, but is particularly intended for use in connection with paper employed to form the 10 outside surface of card-board boxes.

My design consists in initial letters, symbols, or letters and symbols running over the surface of the paper, substantially as shown in the accompanying drawing, which illustrates 15 my design.

The letters and symbols here shown are "E.

& W." They are delineated in various sizes and run in various directions over the paper, crossing one another indiscriminately, substantially as shown.

26

What I claim as my design, and desire to secure by Letters Patent, is—

The design for paper consisting of letters and symbols running in various directions over the paper and crossing each other indiscriminately, substantially as specified and shown. 25

SAMUEL W. WILSON.
